ILLUMINATED STATUETTE

John Elvan, New York, and Anthony Masillo,
Franklin Square, N. Y.

Application June 2, 1948, Serial No. 30,704

4 Claims. (Cl. 240—10)

1

This invention relates to new and useful improvements in an illuminated statuette.

More particularly, the present invention proposes the construction of an illuminated statuette which is useful as a religious article and which includes a devotional object, such as a statuette of a saintly Biblical personage, but which may also be designed for use as a "nite-lite" for a nursery in which event the statuette may be designed after a character of fiction, such as Mickey Mouse, Snow White, or any desired animal, or designed for use as a decorative article for Christmas or other similar holidays, in which event the statuette may be patterned after Santa Claus, after an Easter rabbit or other similar holiday personage or symbol.

A feature of the invention is that the new article is a single and easily portable structure including the statuette or the like, a carrier therefor, as for instance a base to be rested on a horizontal support, and an illuminating means.

According to another feature of the invention, said illuminating means is readily variable as to its manner of illumination of the statuette or the like, as for being changed so as from time to time to highlight a particular portion of the statuette or the like, and in doing so to modify, when desired, the color of the highlighting.

An object of the invention, also, is to provide a relatively inexpensive combination, one which is strong and rugged throughout, yet one which is expeditiously and easily variable as above.

A further object of the invention is to provide a combination as just stated, and one which may practicably be made quite small, particularly for home use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of an illuminated statuette constructed in accordance with the present invention.

Fig. 2 is a plan view of Fig. 1.

Fig. 3 is a partial vertical sectional view through the base only of the statuette.

Fig. 4 is a side elevational view similar to Fig. 1 but illustrating a modification of the invention.

Fig. 5 is a horizontal section, taken on the line 5—5 of Fig. 4.

2

Fig. 6 is a vertical section, taken substantially on the line 6—6 of Fig. 5, with the base and a bottom sealing plate therefor shown partially in side elevation and partially in section, and with the upper portion of the statuette indicated in dot and dash lines and the bottom portion thereof shown in elevation.

Fig. 7 is a top plan view, with the bottom contour of the statuette indicated in dot and dash lines, but omitting the top member of a cage for the light source.

Fig. 8 is a bottom plan view of said top member.

The illuminated statuette according to the present invention, includes a base 10 upon which there is mounted a statuette 11. The statuette is preferably molded of plaster of Paris or other similar material and may be left in its natural color or may be artistically colored as desired.

On the drawing, the statuette is shown fashioned after the likeness of the Virgin Mary, but this is by way of illustration only, as the statuette 11 could equally well be fashioned after the likeness of Jesus Christ or some other religious personage.

The statuette could also be used as a nite-lite in which event the statuette 11 could be replaced by a fictional character, such as Mickey Mouse, Snow White or any desired animal so that the illuminated statuette may be conveniently used in the nursery. Or if desired, the statuette could be designed as a decorative article for use at Christmas or on other holidays, in which event the statuette 11 could be replaced by a statuette of Santa Claus, an Easter rabbit or other similar holiday personage or symbol.

The base 10 is hollow and has an open bottom closed by a removable bottom wall 12. The bottom wall 12 has a reduced inner portion 12a provided on its periphery with screw threads which threadedly engage complementary threads on the inner wall of the hollow base 10.

The interior of the hollow base 10 is preferably filled with a non-conductive filler material 10a such as "Plastic Wood," a ceramic material or other non-conductive resinous plastic material. If desired, the removable bottom wall 12 may be omitted, but it has been found useful in providing a flat surface upon which the statuette may be conveniently rested and giving a finished appearance to the statuette.

A small peanut-type light bulb 13, preferably of the neon-type, is secured in position through the top wall of the hollow base 10 so as to cast its light rays upon the front of the statuette 11.

when the bulb 13 is lit. An electric cord 14 is extended through an opening 15 formed in the back side wall of the hollow base 10. The outer end of the electric cord 14 is provided with the usual plug 16 for insertion into the conventional household electric current receptacle, not shown on the drawings.

Within the base 10, the electric cord 14 has its leads 14^a and 14^b soldered to the projected contacts 17 of the light bulb 13. Soldered in position in the lead 14^a there is a small resistance 18 required in view of the low voltage of the peanut-type electric bulb 13.

It is apparent that with the plug 16 inserted into an electric current outlet receptacle that the light bulb 13 will be lit and its rays of light will light up the front of the statuette producing a very pleasant and religious effect in a darkened room.

In the modification of the invention shown in Figs. 4 to 8, the illuminated statuette comprises a statuette 20, representative of the Virgin Mary. This may be molded of plaster of Paris or of any suitable material, or otherwise made, and left white, cream or ivory colored, or finished in one or more pleasingly contrasting colors.

The bottom of the statuette 20 is secured to a suitable carrier, here shown as a low cylindrical base 21 having a flat bottom and a flat top. This base is hollow, as indicated in Fig. 3, and the base cavity contains a socket 22 for a gaseous electric bulb 24, preferably a rather tiny one relative to the size of the statuette 20, as indicated.

The socket 22 will, of course, be of the type to fit the base of the bulb 24, whether the bulb base be of threaded, bayonet-joint or other kind. The socket 22 is fixed to the base 21 for suspension into the base cavity, with the open top of the socket exposed by a suitable aperture through the top wall of the base 21. The wiring to the socket 22 is indicated at 25, and may go to a suitable current source, A. C. or D. C., and of any voltage, such as afforded by way of a battery or by way of the usual wall receptacle in circuit with a remote current source.

The aforesaid cage for the light source provided by the bulb 22 is shown as comprising a bottom shell member 26, the main portion of which is cylindrical, and a top shell member 27, mainly comprised of a conical-walled annular cap.

The shell member 26 has a major cylindrical tubular portion 28, an annular horizontal portion 29, and a short cylindrical skirt 30 depending from the outer limits of said portion 29. The bottom of said portion 29 rests on the top of the base 21 marginally thereof, and the inside of said skirt 30 fits loosely around the base 21; so that the shell member 26 may be readily rotated relative to the base 21, for the facilitation of which adjustment the skirt 30 is illustrated in Fig. 4 as being externally knurled.

Still referring to the shell member 26, this, in addition to its cylindrical tubular portion 28, includes an internal annular eave 31 shaped like the frustum of an inverted cone. This eave has three openings 32, 33 and 34 therethrough. Along a portion of the inner lower circular edge 35 (Fig. 8) of the eave 31, an extended part 36 of said eave is curled under and upward to provide an arcuate groove 37 opposite the three openings 32, 33 and 34. Three panes 38, 39 and 40 are snapped in place under the eave 31, with each such pane covering a different one of the openings 32, 33 and 34. These panes are of different colors, as, for instance, red, yellow and blue;

and may be made of small rectangular pieces of a colored transparent plastic such as cellulose acetate.

For selectively using an illumination of one color only, at a time, the shell member 27 is provided. This member 27 comprises an eave 41 like the eave 31 and dimensioned to slidably overlie the eave 31, and a cylindrical skirt 42 depending from the upper limits of the eave 41. The skirt 42 has an inside diameter such that the skirt 42 fits all around the top of the shell member 26 for easy turning of the latter relative to the shell member 27. To facilitate turning of the member 27 its skirt 42 is illustrated in Fig. 4 as being externally knurled.

The eave 41 of the shell member 27 has a single opening 43, desirably of the same shape as each of the openings 32, 33 and 34.

With the bulb 24 energized, a particular color for the light rays to illuminate the statuette 20 may be selected by angular adjustment of the shell member 27 on the shell member 26, that is, to align the opening 43 with any one of the openings 32, 33 and 34; and by turning the shell member 26 on the base 21, these light rays may be discharged in a selected direction to highlight a particular part of the statuette. Certain seasons of the liturgical calendar are penitential, others joyous, and others of grievous import; so that, for these, respectively, the red, the yellow and the blue panes 38, 39 and 40 of the shell member 26 would approximately be interposed between the bulb 24 and the opening 43 of the shell member 27. For obtaining maximum illumination from a tiny bulb, the interior of the shell 26 may be painted white, brightly polished, or otherwise suitably treated for high light reflectivity power.

The bottom of the base 21 is desirably sealed, in any suitable way, the closure thereof being in the present case shown as accomplished by use of a sealing plate 44 having a reduced upper cylindrical portion externally threaded to match an internal thread at the lower portion of the base cavity.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. An article of the class described, comprising a statuette, a support on which said statuette is fixed, an electric bulb on said support and positioned to illuminate said statuette means for supplying energizing current to said bulb, and means movable relative to said bulb for highlighting any selected one of various portions of said statuette.

2. An article of the class described, comprising a statuette, a support on which said statuette is fixed, an electric bulb on said support and positioned to illuminate said statuette means for supplying energizing current to said bulb, means movable relative to said bulb for highlighting any selected one of various portions of said statuette, and movable means interposed between said bulb and said statuette; said movable means selectively exposing a plurality of colored filters to the light rays emanating from said bulb and transmitted to said statuette.

3. An article of the class described, comprising a statuette, a support on which said statuette is fixed, an electric bulb on said support and positioned to illuminate said statuette, and means for supplying energizing current to said bulb, there also being means movable relative to said bulb for highlighting any selected one of various portions of said statuette, said last named means including a rotatable shell having an opening therethrough so located thereon that when said shell is rotated said opening is moved through a circular path surrounding a lower portion of said statuette.

4. An article of the class described, comprising a statuette, a support on which said statuette is fixed, an electric bulb on said support and positioned to illuminate said statuette, and means for supplying energizing current to said bulb, means movable relative to said bulb for highlighting any selected one of various portions of said statuette, and movable means interposed between said bulb and said statuette for impart-

ing a selected one of a plurality of different colors to the light rays emanating from said bulb and transmitted to said statuette, each of the second-named and third-named means comprising relating rotatable shells.
